CLAIM

The ornamental design for an immunoassay unit for analysis of biological liquids or the like, as shown and described.

DESCRIPTION

FIG. 1 is a top perspective view of an immunoassay unit for analysis of biological liquids, showing our new design;

FIG. 2 is a top plan view thereof;

FIG. 3 is a side elevational view thereof;

FIG. 4 is a bottom plan view thereof;

FIG. 5 is a rear elevational view thereof.
